(57) **CLAIM**

The ornamental design for a regulated fluid dispensing device, as shown and described.

DESCRIPTION

FIG. 1 is an isometric view of a first embodiment of a regulated fluid dispensing device of my new design.

FIG. 2 is a front view of the regulated fluid dispensing device shown in FIG. 1.

FIG. 3 is a rear view of the regulated fluid dispensing device shown in FIG. 1.

FIG. 4 is a right side view of the regulated fluid dispensing device shown in FIG. 1.

FIG. 5 is a left side view of the regulated fluid dispensing device shown in FIG. 1.

FIG. 6 is a top view of the regulated fluid dispensing device shown in FIG. 1.

FIG. 7 is a bottom view of the regulated fluid dispensing device shown in FIG. 1.

FIG. 8 is an exploded view of the regulated fluid dispensing device shown in FIG. 1.

FIG. 9 is an isometric view of a second embodiment of a regulated fluid dispensing device of my new design,

FIG. 10 is a front view of the regulated fluid dispensing device shown in FIG. 9.

FIG. 11 is a rear view of the regulated fluid dispensing device shown in FIG. 9.

FIG. 12 is a right side view of the regulated fluid dispensing device shown in FIG. 9.

FIG. 13 is a left side view of the regulated fluid dispensing device shown in FIG. 9.

FIG. 14 is a top view of the regulated fluid dispensing device shown in FIG. 9.

FIG. 15 is a bottom view of the regulated fluid dispensing device shown in FIG. 9; and,

FIG. 16 is an exploded view of the regulated fluid dispensing device shown in FIG. 9.

(Continued)

The broken lines are included for the purpose of illustration of portions of the regulated fluid dispensing device that form no part of the claimed design.
